UNITED STATES PATENT OFFICE.

THEODOR HOLZHALB, OF BROOKLYN, NEW YORK, ASSIGNOR TO THE SEGAR STUDIOS INC., A CORPORATION OF NEW YORK.

DESIGN FOR A LIGHTING-FIXTURE BACKPLATE OR SIMILAR ARTICLE.

Application filed June 14, 1926. Serial No. 18,035. Term of patent 7 years.

To all whom it may concern:

Be it known that I, THEODOR HOLZHALB, a citizen of the United States, and a resident of the city of Brooklyn, county of Kings, and State of New York, have invented a new, original, and ornamental Design for a Lighting-Fixture Backplate or Similar Article, of which the following is a specification, reference being had to the accompanying drawing, forming a part hereof.

In these drawings:

Figure 1 is an elevational view of the

lighting fixture back plate or similar article, the part shown in full line outline being ornamented in the same manner as the part more fully illustrated, and

Figure 2 is a diagrammatic side outline view of the same.

I claim:

The ornamental design for a lighting fixture backplate or similar article substantially as shown.

THEODOR HOLZHALB.
